UNITED STATES PATENT OFFICE.

JAMES T. STODDARD, OF PORTLAND, OREGON.

WOOD-REFUSE INCINERATOR.

REISSUED

1,171,005.

Specification of Letters Patent.

Patented Feb. 8, 1916.

Application filed May 24, 1915. Serial No. 30,064.

To all whom it may concern:

Be it known that I, JAMES T. STODDARD, a citizen of the United States, residing at Portland, in the county of Multnomah and 5 State of Oregon, have invented a new and useful Improvement in Wood-Refuse Incinerators, of which the following is a specification, reference being had to the accompanying drawings.

10 My invention relates to that class of devices used to burn the sawdust and other wood-refuse taken from mills or factories engaged in making wood products.

15 The object of my invention is to provide a device of this kind in which the construction is arranged to produce a circulation of cool air upon the inside and outside of its thin metal walls and thus preserve them against destruction from the intense heat 20 developed in burning refuse of that kind, also to secure the best possible draft to the material burned. I attain these objects, as well as other advantages, by the construction, combination and arrangement of 25 parts illustrated in the accompanying drawings, which form a part hereof.

Figure 1 is a side elevation with parts broken away and showing sectional elevation therein. Fig. 2 is a transverse half 30 section on the line 2—2 of Fig. 1. Fig. 3 is a plan view of top, showing spark arrester. Fig. 4 is a cross section of a leg on the line 4—4 of Fig. 1. Fig. 5 is a cross section of leg on the line 5—5 of Fig. 3, showing 35 attachment of spark arrester.

Like letters and numerals refer to like parts throughout the views.

A is the conical body of the incinerator.

B is a concrete circular fire-pit within the 40 same.

In the body A are upright legs 6, of thin channel metal, rigidly secured at their lower ends in footings 7 lodged in the earth. Inside of the legs are placed hoops 8, at various heights and of different sizes, which hoops are rigidly secured to the legs so that a conical frame is formed. A wall 9, of thin sheet metal, (preferably corrugated metal), is provided in sections 10, which are rigidly 45 secured in the said frame to and upon the hoops 8. The legs 6 extend below the lower end of the wall 9 a suitable distance. A conveyer 11 is arranged to extend from a source of material supply to and within the 50 body A at a suitable height therein. A spark arrester 12 is rigidly secured over the

top of the body A. It is supported thereon by suitably curved lateral rods 13 extending below it transversely from the upper ends of the legs 6.

Within the body A the circular pit B is arranged so that its vertical wall shall extend a suitable height above the lower end of the body wall 9 and also to allow a suitable space between the two walls laterally. 65 The fire-pit B is arranged so that its bottom 14 shall be at a suitable height with relation to the pit wall and body wall 9. Below and within the fire-pit B is an ash pit 15 extending laterally across the fire-pit B. The 70 ash pit has a fire grate 16.

Material 17 is shown in position for incineration.

My device should be set up in a suitable 75 location near a refuse material supply place so that the material can be easily conveyed to the incinerator and the danger from conflagration can also be minimized.

A door may be and usually is provided in a convenient position in the body so that the operator can enter the pit and start a fire, also to remove ashes. When the fire is started, sawdust and refuse wood material is sent through the conveyer and deposited in the fire-pit and the incineration is thereafter carried on indefinitely. A draft enters the fire-pit from below through the ash pit, and also there is an abundant draft from the sides to insure speedy and complete incineration of everything deposited.

90 It will be seen that, owing to the conical shape of the body, a chimney effect is produced which makes an excellent combustion draft. It will be further seen that the cold air enters from below, and, while supplying all required for combustion, it also follows upward along the interior of the wall, being directed against it primarily by the opposing outer surface of the fire-pit wall. The upper portion of the body being heated, the 100 air of course naturally rises and the cold air flows constantly over the inner surface as shown by the arrows. On the outer surface of the body it will be noted that as each portion becomes heated the air rises therefrom and cold air constantly rushes against all parts of the outer surface as indicated by the arrows. This, and the thin metal in the wall, insure a temperature so low in the body and the legs that they will never fuse 110 or burn out. In any event the life of the body is conserved indefinitely. I prefer to

use corrugated metal in the wall as it cools quickly and allows for expansion and contraction. For the same reason I use channel iron in the legs. The wall being secured on the inside of the frame protects the latter from the heat. The channels in the legs facing inward also assist in the passage of the cooling drafts upward.

10 The cheapness of construction, positive cooling arrangement, and effective drafts make my device highly successful both as to its management and cost of operation. Its durable quality is also an important feature in cost of maintenance. While the fire-pit 15 is illustrated as circular, it may also be of polygonal or other suitable form.

The spark arrester is easily secured on a device of this form and perfectly prevents all danger of setting out fires.

20 Having thus described my invention, I claim—

1. An incinerator of the character described, comprising a thin metal upright conical body shell A with openings at each

of its ends and open throughout its length, 25 means to support said body at a suitable height, a circular fire-pit within the body, having a vertical pit wall the upper end of which is arranged at a suitable distance laterally from the body shell and also at a 30 suitable height above its lower end, substantially as described.

2. An incinerator of the character described, comprising an upright body with openings at each of its ends and open 35 throughout its length, said body being composed of a frame and a thin metal wall on the inside of the frame, means to support the body at a suitable height, a fire-pit within the body, having a vertical pit wall the 40 upper end of which is arranged at a suitable distance laterally from the body wall and also at a suitable height above its lower end, substantially as described.

JAMES T. STODDARD.
